Primary Examiner — Zenia I Bennett(74) *Attorney, Agent, or Firm* — Andrew F. Young, Esq.;
Lackenbach Siegel, LLP(57) **CLAIM**

The ornamental design for a bracelet lock member, as shown and described.

DESCRIPTION

FIG. 1 is front top perspective view of a bracelet lock member showing my new design.

FIG. 2 is a front bottom perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right side elevation view thereof; and,

FIG. 8 is a left side elevation view thereof.

No claim is made to portions which are not shown. The dash-dash lining indicates disclaimed portions to which no claim is made. The dash-dot-dash lining indicates claim boundaries beyond which no claim is made. The surfaces are lined for contour only.

1 Claim, 5 Drawing Sheets(56)
